UNITED STATES PATENT OFFICE.

OLE T. BEKKERUS, OF HURDSFIELD, NORTH DAKOTA.

COVER FOR TANKS.

Application filed January 26, 1925. Serial No. 4,680.

This invention relates to a cover adapted to be placed on a tank or receptacle from which oils or liquids, preferably of a volatile nature, are to be removed. Certain tanks 5 in which gasoline and other volatile liquids are transported have a top or top portion comprising a circular flange or rim and also have an aperture through said top, in which a pipe is disposed for removing the gasoline. When the gasoline or other volatile liquid is so removed there is usually quite a space around the tank and considerable leakage and evaporation of the volatile liquid occurs.

15 It is an object of this invention, therefore, to provide a device adapted to be used in connection with such a tank which will fit closely thereover and around the removing pipe so that leakage and evaporation of the 20 liquid in any appreciable amounts will be prevented.

It is a further object of the invention to provide such a device comprising a cover having a flange projecting downwardly 25 therefrom adjacent its edge with means below the flange to closely engage the top of the tank, said cover also having an aperture therethrough, and means carried adjacent the aperture to closely engage the pipe extending into the tank.

It is also an object of the invention to provide such a cover, as set forth in the preceding paragraph, having a portion adjacent one edge pivoted for outward swinging 35 movement, said cover having a lateral opening extending to said aperture which is exposed when said swinging portion is swung outwardly whereby the cover can be placed on the tank with the pipe in position and 40 the pipe can be closely engaged when the swinging portion is again swung inwardly.

These and other objects and advantages of the invention will be fully set forth in the following description made in connection with the accompanying drawings in which like reference characters refer to the same parts throughout the different views; and in which,

Fig. 1 is a plan view of the device showing the removable pipe in cross section and showing the swinging portion of the cover in a different position in dotted lines;

Fig. 2 is a view partly in side elevation and partly in vertical section; and

Fig. 3 is a vertical section taken on the line 3—3 of Fig. 1.

Referring to the drawings, the top of the tank or receptacle in which liquid is to be transported is shown as 4, said tank having a top portion 5 upturned at its edges and forming with the side of the tank a circumferential upstanding flange portion 4^a. Said top 5 also has an aperture 5^a therethrough surrounded by an upstanding flange 5^b which may be closed by any suitable block 60 or cover and which, in the embodiment of the invention illustrated, is shown as being 65 interiorly threaded to receive a closure member. When the liquid is to be removed from the tank a pipe 7 may be placed down into the tank through the opening 5^a, the liquid being pumped through the pipe 7 and directed to the desired place.

In accordance with the present invention, a cover member 8 is provided made of sheet 75 material, preferably metal, and which will be made of the same shape as the tank 4, which, in the embodiment of the invention, is shown as circular. The cover 8 has a flange 9 projecting downwardly therefrom, 80 adjacent its edge, which flange is angular in cross section and riveted or otherwise suitably secured to the cover 8. Outside of the flange 9, a gasket ring 10 is disposed, which, when the cover is in position on the 85 tank, is adapted to closely engage the flange 4^a. The flat top of cover 8 has an aperture 8^a formed therein of semi-circular shape at its inner portion having straight sides tangent to said semi-circular portion and substantially parallel to a radius passing through the center of said semi-circular portion. The opening 8^a extends to the edge of the cover 8. At the inner side of the opening 8^a an angular flange 11 of semi-circular shape is secured having inturned 90 spaced pointed portions 11^a, said points overhanging the portion between the vertical wall of the flange 11 and the edge of the opening 8^a. A semi-circular gasket member 12 is disposed between the points 11^a and the portion of the cover inside of flange 11 and clamped in such position. A swinging member 13 is provided which is pivoted at 13^b, 95 which member is of the shape shown in Fig. 1 and has a pin 14 projecting downwardly therefrom adapted to spring into a hole in a latch plate 15 secured to the top of cover 8. The member 13 has a short gasket member 16 at its underside adapted to fit between the ends of the gasket 10 which is 100 cut away to accommodate the gasket 16 ad-

105
110

adjacent the opening 8^a. The member 13 also has a semi-circular opening 13^a at its inner side which is surrounded a short distance from its edge by the upstanding semi-circular flange 17 which has inwardly directed points 17^a, the flange 17 being substantially concentric with the flange 11, the semi-circular portion of aperture 8^a also being concentric with the opening 13^a. A gasket member 18 of semi-circular form is clamped between the points 17^a and the top of member 13. The cover 8 has a handle 19 disposed at its center by which the same can be manipulated.

15 In operation, after the pipe 7 has been disposed in the tank for the removal of the liquid the cover 8 is placed in position. This can be done by swinging outwardly the section 13, as shown in dotted lines in Fig. 1, 20 and moving the cover into place laterally, the pipe 7 passing through the opening 8^a. The gaskets 10 and 16 will then be pressed down on the top of flange 4^a and the member 13 will then be swung to closed position 25 with the latch 15 engaged with pin 14. When this is done the gaskets 12 and 18 will closely engage the pipe 7. A tight closure is thus provided for the tank 4 and in the opening 5^a therethrough and no substantial portion of the liquid can leak or evaporate.

From the above description it is seen that applicant has provided a very simple and efficient device for preventing leakage and 35 evaporation from liquid stored and transported in tanks. The device is simple and easily constructed and can be produced at low cost. By the use of the same a great saving in oil and other liquid is accomplished. The device has been amply demonstrated in actual practice and found to be 40 very successful and efficient.

It will, of course, be understood that various changes may be made in the form, details, arrangement and proportions of the parts without departing from the scope of applicant's invention, which, generally stated, consists in the novel parts and combination of parts disclosed and defined in 50 the appended claims.

What is claimed is:

1. In a container having an aperture therein through which a pipe is adapted to extend, an angular semi-circular flange secured to the container adjacent an edge of

said aperture, a semi-circular closure plate pivoted to said container adjacent another edge of said aperture, an angular semi-circular flange mounted on said closure plate and a split ring of packing material secured to each of said flanges, said split rings of packing material being adapted to co-operate to clamp about a pipe extending through said aperture and form a fluid tight joint between the container and the pipe when said closure plate is swung toward the flange secured to said container, said flanges having a plurality of inwardly extending pointed portions at their upper inner edges securing said split rings of packing material to said flanges.

2. In a container having an opening therein at the joint between one side and one end thereof, a flange fixed to the end of the container adjacent the inner edge of the open portion at the end of the container, a closure member pivoted to the container and adapted to close the open portion at the side of the container and the outer part of the open portion at the end of the container, a split ring of packing material carried by said flange, a split ring of packing material carried by said closure member, and means for holding said closure member in closed position, said split rings of packing material being adapted to encompass a pipe inserted within said aperture to provide a fluid tight joint between the container and the pipe.

3. In a container having an aperture through one end adjacent one side thereof, said container being capable of receiving a pipe through said aperture, said side being cut out adjacent said aperture to form a side opening in said container communicating with said aperture, a flange fixedly secured to said top adjacent the inner side of said aperture, a swinging plate pivoted to said top, a pad of packing material secured to the lower side of said plate and adapted to close the side opening in said container as said plate is swung inwardly, a flange carried by said plate, and pads of resilient material carried by each of said flanges, said last mentioned pads being adapted to co-operate to tightly embrace a pipe inserted through said aperture as said plate is swung inwardly.

In testimony whereof I affix my signature.
OLE T. BEKKERUS.
